UNITED STATES PATENT OFFICE.

JAN KULHÁNEK, OF PRAGUE, AUSTRIA-HUNGARY.

SEMIPERMANENT PORTABLE BUILDING.

SPECIFICATION forming part of Letters Patent No. 728,471, dated May 19, 1903.

Application filed July 21, 1902. Serial No. 116,440. (No model.)

To all whom it may concern:

Be it known that I, JAN KULHÁNEK, residing at Prague, in the Empire of Austria-Hungary, have invented certain new and useful 5 Improvements in Semipermanent Portable Buildings, of which the following is a specification.

My invention relates to portable buildings, and has for its object the improved construction of such portable and semipermanent buildings, the main feature of which consists in the sides or walls or such parts thereof as are situated between another wall and a window or door, or between the foundation and 10 the window, or between the window or door and the ceiling, being formed of one single piece, by preference of artificial stone, having the door and window frames, as well as the lining of said frames, permanently attached in such manner that in jointing the 15 different plates the door and window frames will also become jointed and ready for the hanging of the doors and windows.

Another novel feature is the improved manner of connecting the different plates.

In the annexed drawings an improved building of this kind is shown, of which—

Figure 1 is a perspective view with some of the plates raised away from each other to show 20 the manner of their jointing. Fig. 2 shows, on a reduced scale, a horizontal section and the ground plan of a building of the most simple kind according to my invention. Fig. 3 is a partial section, enlarged, on line A B 25 of Fig. 2. Figs. 4 and 5 are sections on lines C D and F G of Fig. 1, showing the manner in which the corner-plates are jointed.

In all figures similar letters of reference indicate corresponding parts.

For erecting a building according to my invention a suitable foundation may be built 30 in the ordinary manner, according to the desired ground-plan of the house. Upon this foundation are placed the side plates *a a*, which have a thickness of from about four to twenty inches and are made of artificial stone 35 of any known or suitable kind. In molding the plates which adjoin a door or window opening the adjoining part *m* of the door or window frame, together with its lining *n*, is placed into the mold, so that frame and lining will appear permanently and rigidly

connected with the plate after the composition has set. I consider this mode of attachment as the most advantageous; but the 45 frames and linings may also be attached to the plates, after they have been cast, in any other suitable manner.

The plates *a* are connected by rabbet-joints, the ledges *b* being less than half as thick as 50 the plates, so that an opening *p* will remain between each pair of ledges, as shown in Figs. 3, 4, and 5. In the corners formed by the rabbet-ledges *b* are placed rings *c* of eye-bolts, which are by preference embedded into 55 the plates, and the size of the rings about corresponds to the cross-section of the openings *p*, formed by the rabbet-ledges. The plates are held together by iron rods *q*, which are pushed through the hollow space *p* and 60 through the rings *c* of both plates. At their ends these rods *q* are provided with eyes, through which a key *g* is driven to draw and hold the plates tightly together. The openings *p* upon the outside of the building are 65 closed up by cement, mortar, or in any other suitable manner. Rods *q* are drawn through the vertical joints of the plates, as well as through the horizontal ones.

In buildings having a ground-floor only the 70 ceiling also forms the roof; but where there is another story the ceiling of the one forms the floor of the next story. The ceiling or roof is formed of plates *d*, which are jointed similar to the plates *a* and which may have 75 a core of wire-netting, perforated sheet-iron, or of similar material for increasing their strength. The roof or ceiling plates *d* are attached to the walls by passing the vertical rods *r* of the latter through them. On top 80 of the plates *d* countersunk washers are placed upon the ends of the rods *r*, which latter are screw-threaded, so that the whole may be drawn and held together by means of nuts. The recesses in the plates in which 85 the washers and nuts are countersunk are then filled out with plaster, mortar, or such like. When the ceiling-plates *d* serve as floor-plates for another story, they may be provided with a suitable covering on top— 90 such as, for instance, of xyloolith or similar material. In all cases it is advisable to provide a suitable covering for the roof-plates *d* and to calk the joints of these, as well as 95 100

of the wall-plates, with moss, oakum, or such like or to cast them out with asphalt.

Buildings constructed in this manner may at any time be taken apart, transported, and 5 put up again without loss of material. For this reason such buildings are particularly useful in cases where temporary housing is to be provided for a large number of people.

Having thus fully described my invention, 10 what I claim as new, and desire to secure by Letters Patent of the United States, is—

1. In a portable building, the combination with two, adjacent wall-plates of artificial stone provided with rabbets in the adjoining 15 edges with an opening between the ledges of said rabbets, of eyebolts embedded in said plates and having their rings in said opening |

in line with each other, a rod passed through said rings and having eyes at its ends, and keys driven in said eyes substantially as and 20 for the purposes set forth.

2. A portable building comprising wall-plates of artificial stone having the adjacent parts of the window and door frames and their linings secured permanently to said 25 plates during the operation of molding the plates, substantially as and for the purpose set forth.

In testimony whereof I affix my signature.

JAN KULHÁNEK.

In presence of—

HANS DÜRKE,
ADOLPH FISCHER.
